[57] **CLAIM**

The ornamental design for a head for an electric massage apparatus, as shown and described.

DESCRIPTION

FIG. 1 is a front elevational view of a head for an electric massage apparatus, showing our new design;
FIG. 2 is a rear elevational view thereof;
FIG. 3 is a top plan view thereof;
FIG. 4 is a bottom plan view thereof;
FIG. 5 is a right side elevational view thereof;
FIG. 6 is a left side elevational view thereof;
FIG. 7 is a perspective view showing the top, front, and a portion of the right side thereof;
FIG. 8 is a perspective view of a second embodiment of the head for an electric massage apparatus;
FIG. 9 is a top plan view thereof;
FIG. 10 is a bottom plan view thereof;
FIG. 11 is a right side elevational view thereof;
FIG. 12 is a left side elevational view thereof;
FIG. 13 is a rear elevational view thereof; and,
FIG. 14 is a front elevational view thereof.
